UNITED STATES PATENT OFFICE.

MAX JASPER, OF BERLIN, GERMANY.

SAFETY-CLOSURE FOR CONTAINERS OF INFLAMMABLE LIQUIDS.

1,076,830.

Specification of Letters Patent.

Patented Oct. 28, 1913.

Application filed September 18, 1912. Serial No. 720,940.

To all whom it may concern:

Be it known that I, MAX JASPER, a citizen of Germany, residing at Berlin, Germany, have invented a new and Improved Safety-
5 Closure for Containers of Inflammable Liquids, of which the following is a specification.

This invention relates to a safety closure for bottles, jars, cans and similar containers of inflammable liquids. The closure is adapted to be fitted into the mouths of such containers as are provided with but a single ingress and egress opening, so that it permits the pouring in as well as the pouring 15 out of the liquid. The construction should be such that the closure cannot be readily removed by unauthorized persons. So also the closure should effectively prevent the flame from striking inward, for which purpose it should be made to effectively conduct the heat generated, which latter purpose is rendered more difficult by the location of the closure within the mouth of the container.

The invention comprises essentially an 25 elongated wire net which is fitted into the mouth of the container conjointly with a metal body of a relatively large size, which besides constituting a heat conductor, also serves to attach the net to the container.

30 In the accompanying drawing: Figure 1 is a longitudinal section of part of a container embodying my invention; Fig. 1^a a similar section showing the container in side view; Fig. 2 a plan on a reduced scale; Fig. 3 a detail of the tongues for removing the closure; and Fig. 4 a side view partly in section of a modification of the invention.

Referring more particularly to Figs. 1, 1^a and 2, the letter A represents the neck of a 40 bottle, jar, can or other container of inflammable liquids. Into this neck is fitted a foraminated or small meshed wire tube or elongated sack a, tapering toward its bottom, while the upper end of the tube is open. Tube 45 a is surrounded by a cylindrical metal shell b to which it is suitably secured at its upper end in a heat transmitting manner. Shell b has an upper flaring section or head c and is provided below said section with a plurality

of upright slits d. The strips formed by 50 these slits are bulged outwardly to constitute a plurality of convex resilient lamellæ e. Head c prevents the device from being pushed into the bottle neck to an undue extent, while lamellæ e prevent it from dropping out said head and lamellæ engaging the vessel respectively above and below a contraction formed within the bottle neck. Within the mouth of tube a is fitted a thimble shaped wire frame r which may be soldered or otherwise secured to the tube. This frame prevents the tube from being broken by the introduction of a funnel, and also constitutes a means for the withdrawal of the device from the bottle. This withdrawal is 60 effected by tongs t (Fig. 3) having notched jaws u that are projected into the frame to engage diametrically opposed sections s thereof, so that by a pull on the tongs, the device will become unseated against the action of the resilient strips e.

As shown in Fig. 4, there may be fitted into the wire tube a, an inner foraminated sheet metal tube v, which serves to protect tube a and also constitutes an efficient conductor of heat.

It is obvious that changes may be made in the construction of the safety device without departing from the spirit of my invention.

I claim:

80 A safety closure for containers of inflammable liquids, comprising a shell having a head adapted to be seated within the neck of said container and a resilient bulged section below said head that is adapted to frictionally engage said neck, a reticulated sack depending from the shell-head into the shell, and an openwork thimble extending from the shell-head partly into the sack, said thimble constituting a guard for checking 85 the introduction of a liquid-charging funnel, and constituting likewise exteriorly accessible means for withdrawing the closure from the container.

MAX JASPER.
